UNITED STATES PATENT OFFICE.

WALTER CLINTON PETTEE, OF NEW YORK, N. Y.

FOUNTAIN DRAWING OR RULING PEN.

SPECIFICATION forming part of Letters Patent No. 727,433, dated May 5, 1903.

Application filed July 29, 1902. Serial No. 117,530. (No model.)

To all whom it may concern:

Be it known that I, WALTER CLINTON PETTEE, a citizen of the United States, and a resident of the city of New York, borough of Manhattan, in the county and State of New York, have invented a new and Improved Fountain Drawing or Ruling Pen, of which the following is a full, clear, and exact description.

The invention relates to drawing instruments; and its object is to provide a new and improved drawing or ruling pen which is simple and durable in construction and arranged to supply ink to the pen-points without the ink unduly drying up, and permitting convenient setting, filling, and cleaning whenever desired.

The invention consists of novel features and parts and combinations of the same, as will be more fully described hereinafter and then pointed out in the claims.

A practical embodiment of the invention is represented in the accompanying drawings, forming a part of this specification, in which similar characters of reference indicate corresponding parts in all the views.

Figure 1 is a side elevation of the improvement. Fig. 2 is a sectional side elevation of the same. Fig. 3 is a sectional plan view of the same on the line 3 3 of Fig. 1, and Fig. 4 is a similar view of the same on the line 4 4 of Fig. 1.

The pen-points A and A', of spring-steel, have their shanks A² and A³ removably secured to opposite sides of an ink-reservoir B for containing liquid ink to be supplied to the pen-points at their inner faces and in close proximity to the terminals thereof, and for this purpose the tubular reservoir B is provided with a tubular tapering end B', extending between, but free of, the pen-points A and A', as plainly shown in the drawings, the outlet of the said tapering end being split transversely to form members B² B³, curved outwardly in opposite directions toward the inner flat faces of the pen-points A and A', as plainly indicated in Fig. 2, to contact with the said faces of the pen-points to insure a ready flow of ink from the reservoir B equally to both pen-points A and A'.

In order to set the pen-points A and A' for heavier or finer lines, a handle C is provided inclosing the reservoir B and held lengthwise

adjustable relative to the reservoir and the pen-points. The lower end of the handle C is for the purpose mentioned arranged to engage inclines or bevels A⁴ and A⁵, formed on the pen-points adjacent to the shanks A² A³, so that when the handle is moved downward this lower end engages the said inclines or bevels A⁴ A⁵ to press the pen-points toward each other for reducing the space between the terminals of the pen-points to set the same for drawing finer lines. When the handle C is shifted upward, then the inherent resiliency of the pen-points A and A' causes the same to open to increase the space between the terminals, thus setting the pen-points for heavier lines.

In order to shift the handle C lengthwise relative to the pen-points, various means may be employed. For instance, the upper end of the handle C may be provided with bearings C' for engaging the peripheral face of a nut D, screwing on the upper threaded end B⁴ of the reservoir B. Now when the operator turns the nut D in one direction to screw the nut downward on the reservoir B then it carries the handle C along to cause the latter to act on the inclines or bevels A⁴ A⁵ to close the pen-points, as previously explained, and when the nut D is turned in the opposite direction to screw the same upward on the threaded end B⁴ then the handle C is moved in a like direction and the pen-points A and A' are free to open by their own resiliency.

In order to clean the lower contracted outlet of the end B', I provide a needle E, extending lengthwise in the reservoir B and passing through the upper closed end thereof to support a knob E', adapted to be taken hold of by the operator to push the needle in and out of the outlet to clean the same whenever necessary. The needle E also carries a piston F within the reservoir B, so as to draw the ink into the reservoir when moving the knob E' outward at the time the end B' is inserted in ink to be filled into the reservoir.

I do not limit myself to the particular construction described, as the same may be varied without deviating from the spirit of my invention.

Having thus described my invention, I claim as new and desire to secure by Letters Patent—

1. A drawing or ruling pen, comprising a reservoir for ink having a reduced tubular end, pen-points between which the said end of the reservoir extends, and means for adjusting the pen-points, as set forth.
2. A drawing or ruling pen provided with pen-points, and a reservoir having a reduced tapering end formed with a split, to produce two members curved outwardly toward the inner faces of the pen-points, as set forth.
3. A fountain drawing or ruling pen, comprising a reservoir for ink and provided with a tapering outlet, pen-points secured on the reservoir and projecting therefrom, free and outside of the said outlet of the reservoir, and means for adjusting the pen-points for drawing heavier or lighter lines, as set forth.
4. A fountain drawing or ruling pen, comprising a reservoir for ink and provided with a tapering outlet, pen-points secured on the reservoir and projecting therefrom, free and outside of the said outlet, the said pen-points being formed with bevels, an adjusting device for the pen-points, consisting of a tubular handle for inclosing the reservoir and engaging the bevels on the pen-points, and means for shifting the handle lengthwise, relative to the pen-points and reservoir, as set forth.
5. A fountain drawing or ruling pen, comprising a reservoir for ink and provided with a tapering split outlet, pen-points secured on the reservoir and projecting therefrom, free and outside of the tapering outlet, and a manually-controlled needle in the reservoir, for cleaning the said outlet, as set forth.
6. A fountain drawing or ruling pen, comprising a reservoir for ink and having a tapering outlet, pen-points secured on the reservoir and projecting therefrom, free and outside of the tapering outlet, and a manually-controlled piston in the said reservoir, as set forth.
7. A fountain drawing or ruling pen, comprising a reservoir for ink and having one end formed into a tapering outlet and the other end threaded, pen-points secured on the reservoir and projecting therefrom, free and outside of the said outlet, said pen-points having bevels, a handle inclosing the said reservoir and engaging with one end the said bevels, the handle being provided at the other end with bearings, and a nut screwing on the threaded end of the reservoir and held in the said bearings, as set forth.

In testimony whereof I have signed my name to this specification in the presence of two subscribing witnesses.

WALTER CLINTON PETTEE.
